UNITED STATES PATENT OFFICE

95,002

DESIGN FOR A HANDLE OR SIMILAR ARTICLE

Otto E. Uhlmann, Grand Rapids, Mich., assignor to Keeler Brass Company, Grand Rapids, Mich.

Application December 24, 1934, Serial No. 54,587

Term of patent 3½ years

To all whom it may concern:

Be it known that I, Otto E. Uhlmann, a citizen of the United States, residing at the city of Grand Rapids, in the county of Kent and State of Michigan, have invented a new, original, and ornamental Design for a Handle or Similar Article, of which the following is a specification, reference being had to the accompanying drawing, forming a part thereof.

Fig. 1 is a front view, and

Fig. 2 is a side view showing my new design, the dominant feature of which is the horizontal leaf cross with the husk on either end.

I claim:

The ornamental design for a handle or similar article as shown and described.

OTTO E. UHLMANN.
